Term of patent 14 years

Int. Cl. D16—99

U.S. Cl. D61—1

FIG. 1 is a front perspective view of an inflatable projection screen embodying my design;

FIG. 2 is a rear perspective view of the same;

FIG. 3 is a front elevational view thereof;

FIG. 4 is a rear elevational view thereof; and

FIG. 5 is a side elevational view thereof.

A side elevational view taken from the side opposite that shown in FIG. 5 is substantially a mirror image thereof.

I claim:

The ornamental design for an inflatable projection screen, as shown and described.
